UNITED STATES PATENT OFFICE.

SALLY PLAUT, OF DUSSELDORF, GERMANY.

HUMMING-TOP.

1,004,814.

Specification of Letters Patent.

Patented Oct. 3, 1911.

Application filed December 19, 1910. Serial No. 598,148.

To all whom it may concern:

Be it known that I, SALLY PLAUT, a citizen of Germany, residing at Dusseldorf, Germany, have invented new and useful 5 Improvements in Humming-Tops, of which the following is a specification.

This invention relates to a humming top which on being spun is adapted to consecutively produce a number of different notes 10 or chords so that a pleasing musical effect is obtained.

In the accompanying drawing: Figure 1 is a vertical section of a humming top embodying my invention; and Fig. 2 a horizontal section on line 2—2, Fig. 1.

The hollow body or shell *a* of the top is provided with upper and lower perforated disks *a'*, *a''* through which extends loosely a spindle *d* having upper knob or handle *d'*. 20 Within body *a*, spindle *d* is provided with a collar *d''* by means of which a lower disk *c* is firmly secured to the spindle. Upon disk *c* is rotatably supported a coacting annular reed plate *b* which is attached to body *a* 25 and by means of which the latter is supported on the spindle. The reeds *b'* of plate *b* are radially arranged, and plate *c* has similar radial slots *c'* the number of slots being however less than that of the reeds, 30 the drawing showing the use of twelve reeds and four slots. It will be seen that by shifting the relative position between body *a* and spindle *d* the slots will become alined with different groups of reeds, so that different notes or chords will be sounded, the 35 air entering through apertures *a''* formed in body *a* above plate *b* and leaving through apertures *a'* below plate *c*. Upon spindle *d* may be mounted an upright circular vane *d''* 40 which serves to increase the volume of sound by driving the air toward egress openings *a'*. Below handle *d'*, body *a* is provided with a neck *a''* around which the usual spinning cord is adapted to be wound.

45 The lower end of spindle *d* protrudes from body *a* and is received within a ferrule *e* within which the spindle is rotatable and tiltable. Ferrule *e* is provided with a protruding foot *l* made of cork, rubber or similar soft material. Foot *l* is surmounted by a cork plate *k* supporting a bearing *i* perforated as at *m*. Upon this bearing is free 50 to glide a shoe *h*, the lower face of which is bulged as shown. Shoe *h* has an upper

central indentation into which sets the 55 lower pointed end *d''* of spindle *d*. To prevent a disengagement of ferrule *e* from spindle *d*, the latter is provided above point *d''* with a circumferential groove *d''* into which enters a perforated flexible disk *f* which is 60 slipped over point *d''*. Disk *f* and consequently spindle *d* is confined within ferrule *e* by an upper perforated plug *g* driven into the ferrule and between which and disk *f* a metal plate *n* is interposed. The bore of 65 plug *g* is such that spindle *d* is not only freely rotatable within the ferrule, but that it is also tiltable relatively thereto.

When the top has been started, the parts *a* and *d* will incipiently rotate with like speed 70 to sound a chord. During this rotation ferrule *e* will be taken along, but owing to the frictional engagement of flexible foot *l* with the floor the ferrule will be retarded relatively to the spindle. As the top during 75 spinning does not maintain its vertical position but rolls from side to side, spindle *d* will be deflected within the ferrule, this deflection causing a tilting movement of shoe *h* on bearing *i*. This tilting movement together with the lateral displacement of the spindle within the foot and the resulting frictional engagement between the spindle and plug *g* causes a retardation of the spindle, while the rotation of body *a* remains unchanged. In this way plate *b* is shifted on 85 plate *c*, so that different groups of reeds *b'* become successively alined with slots *c'*, thus producing the desired change of tune.

I claim:

1. A humming top comprising a spindle, a shell rotatable thereon, a pair of co-acting sound producing disks secured to the spindle and shell respectively, a ferrule loosely encompassing the lower end of the spindle, a 95 slideable shoe engaged by the spindle, and a bearing for said shoe within the ferrule.

2. A humming top comprising a spindle, a shell rotatable thereon, a pair of co-acting sound producing disks secured to the spindle 100 and shell respectively, a ferrule loosely encompassing the lower end of the spindle, a slideable shoe engaged by the spindle, a bearing for said shoe within the ferrule, a resilient foot below the bearing, and spindle- 105 confining means above the shoe.

3. A humming top comprising a spindle, a shell rotatable thereon, a pair of co-acting

sound producing disks secured to the spindle and shell respectively, a ferrule loosely encompassing the lower end of the spindle, a 5 slideable shoe engaged by the spindle, a bearing for said shoe within the ferrule, a resilient foot below the bearing, a disk fitted to the spindle above the shoe, and a plug

located within the ferrule above said disk and perforated for the accommodation of the spindle.

SALLY PLAUT.
